Attorney:

UNITED STATES PATENT OFFICE.

FREDERICK A. STEVENS, OF PROVIDENCE, RHODE ISLAND, ASSIGNOR TO STEVENS AND COMPANY, INCORPORATED, A CORPORATION OF RHODE ISLAND.

MOUNTING.

1,274,807.

Specification of Letters Patent. Patented Aug. 6, 1918.

Application filed October 13, 1917. Serial No. 196,518.

To all whom it may concern:

Be it known that I, FREDERICK A. STEVENS, a citizen of the United States, residing at Providence, in the county of Providence and State of Rhode Island, have invented certain new and useful Improvements in Mountings, of which the following is a specification.

My invention relates to mountings of the finger piece type for eyeglasses and spectacles.

In this type of mountings it is desirable, in order to distribute the strain and avoid excessive wear, that there be a substantial bearing area of the lever arm upon the relatively fixed pivot member or post. For this reason an axial tube or sleeve, formed on the arm, surrounds the entire length of the pivot member. This has proved unsatisfactory because the upper coil or coils of the helical actuating spring which embrace the sleeve are worn and weakened by the oscillation of the sleeve when the arm, to which the movable end of the spring is attached, is vibrated. Furthermore the upper spring coil, which was nearest the fixed end of the spring exerted such pressure against the sleeve that the movement of the latter tended to bind or to exhaust and derange the spring after much use.

The essential objects of my invention are to overcome the enumerated disadvantages and to attain in a single structure the advantages of an extended lever bearing without injury to the bearing or to the spring; also to insure a smooth and unimpeded oscillation of the lever; and to attain these ends in an inexpensive structure embodying a minimum of parts.

In the accompanying drawings which form a part of this specification,

Figure 1 is a front elevation of a pair of eyeglasses embodying my invention,

Fig. 2, a plan view of the device,

Fig. 3, an enlarged section on line 3—3 of Fig. 2, and

Fig. 4, a similar section on line 4—4 of Fig. 3.

Like reference characters indicate like parts throughout the views.

In the form of my invention herein shown 5 represents the lenses, 6 the bridge or nose piece, 7 the flattened supports or bridge end portions, 8 the straps, 9 the lugs, and 10 the 55 lens attaching screws of a pair of eyeglasses

or spectacles. In conjunction with these parts are the operating levers 12 having the finger portions 13 and nose guard portions 14 upon their respective ends. The intermediate portion of each lever has an opening 16 bounded by a vertical tube or sleeve 17.

Each end portion 7 of the bridge has a threaded opening 19 to receive the threads 21 of the reduced end 22 of a post having 65 a body or shank portion 24 of greater diameter, forming a resulting shoulder 25 which abuts against the upper face of the support. The upper portion 26 of the post is of enlarged diameter forming an annular 70 shoulder whose lower face slidably engages a flat ring 27 loose on the post and resting upon the upper end of the tube 17 which also surrounds the portion 24 of the post. The diameter of the shoulder 26 is of such 75 dimension that its periphery is continuous with that of the outer faces of the ring and tube. On top of the shoulder 26 is a laterally extending circular head 28 provided in this instance with a slot 29 to receive a 80 screw driver.

The actuating spring 30 is helical in form, comprising a plurality of superposed coils. The upper coil or coils 31 thereof embraces the cylindrical shoulder 26 and the remaining coils 32 loosely surround the ring 27 and sleeve 17 of the guard. Continuous with the upper coil of the spring is the rearwardly directed arm or end 34 whose bent end presses against the rear of the adjacent 85 strap 8. The lowermost of the coils 32 rests upon the lever 12 and is continued rearwardly to form an arm 36 whose end 37 is laterally bent to engage the rear portion of the lever arm 12.

The effect of each spring 30 is to press the guards 14 inwardly toward each other upon the nose of the wearer, and release of the guards is attained by manually compressing the finger portions 13 of the levers. The 100 spring arm 34 is relatively stationary, and the arm 36 is radially movable. It will be observed therefore, that the uppermost coil 31 is the one which is most violently or strongly engaged with its surrounded member. That is to say the post presses most intensely upon the coil at or adjacent the point 40, as shown in Fig. 4, whenever the lever 12 is operated. This tension or grip, therefore, is exerted on the stationary mem- 105 110

ber or post 26 exclusively, and not upon the ring or oscillatory member 17, by reason of which fact not only is there no grinding or wearing action upon the spring, but also 5 no impediment to the oscillatory movement of the sleeve. During stress on the spring there is some frictional contact of the lower coils 32 with the ring or sleeve, as shown in broken lines in Fig. 3. The friction between 10 the spring and sleeve is lessened by the presence of the ring 27 in conjunction with the sleeve 17 and the lever operates with increased freedom.

Having thus described one illustrative embodiment of my invention, it is understood 15 that the specific terms employed are used in a descriptive sense only, and are not for the purpose of limitation, the scope of the invention being defined by the appended 20 claims.

I claim:

1. In an eyeglass or spectacle mounting, the combination with the frame, of a post 25 upon the frame, a cylindrical shoulder upon the post, a head on the shoulder, an operating arm resting against the frame, a sleeve upon the arm journaled upon the post and below the shoulder, a helical spring surrounding the shoulder and the sleeve, an arm

upon one end of the spring engaging the 30 frame, and an arm on the other end of the spring engaging the operating arm.

2. In an eyeglass or spectacle mounting, the combination with the frame, of a post 35 upon the frame, a shoulder upon the post, an operating arm, a sleeve upon the arm journaled on the post adjacent the shoulder, a helical spring comprising an end coil embracing the shoulder only, and other coils surrounding the sleeve, an arm continuous 40 with said end coil engaging the frame, and an arm upon the second mentioned coils engaging the operating arm.

3. In an eyeglass or spectacle mounting, the combination with the frame, of a post 45 upon the frame, a shoulder upon the post, an operating arm, a sleeve upon the arm journaled upon the post, a ring loose upon the post engaging the sleeve and shoulder, a helical spring comprising an end coil embracing the shoulder only, a coil surrounding 50 the ring and the sleeve, an arm continuous with said end coils engaging the frame, and an arm upon the second mentioned coils 55 engaging the operating arm.

In testimony whereof I have affixed my signature:

FREDERICK A. STEVENS.
